UNITED STATES PATENT OFFICE.

FRED L. CAIN AND CONRAD J. DORFF, OF CHICAGO, ILLINOIS, ASSIGNEES TO HARVARD ELECTRIC COMPANY, OF CHICAGO, ILLINOIS, A CORPORATION OF ILLINOIS.

OUTLET-BOX HANGER.

1,133,535.

Specification of Letters Patent. Patented Mar. 30, 1915.

Application filed August 11, 1914. Serial No. 856,286.

To all whom it may concern:

Be it known that we, FRED L. CAIN and CONRAD J. DORFF, citizens of the United States of America, and residents of Chicago, in the county of Cook, State of Illinois, have invented certain new and useful Improvements in Outlet-Box Hangers, of which the following is a specification.

This invention relates to that class of hangers which are adapted for attachment between adjacent joists or like parts of building structures for the support of outlet boxes, electroliers and the like, in a laterally adjustable manner. And the present improvement has for its object to provide a simple and efficient structural formation and combination of parts, affording a ready and secure clamping together of the hanger bar and the carrier head, a simple and effective attachment of the outlet box, and a convenient means for the attachment of the tubular electrolier stem of the ordinary standard size, all as will hereinafter more fully appear.

25 In the accompanying drawing: Figure 1, is a sectional elevation illustrating the general arrangement of parts in the present invention. Fig. 2, is a plan view of the same.

Similar reference numerals indicate like parts in both views.

Referring to the drawing, 1 represent portions of two adjacent joists or like members of a building structure, to which the present invention is applied.

35 2 designates the usual hanger member spanning the space between the joists 1, aforesaid, and provided at its respective ends with angle flanges or bends 3, by which the hanger member is attached to said joists by screws or like fastening means.

In the preferred construction shown, the hanger member 2 is formed by two flat metal strips or bars 2' and 2'' arranged side by side and capable of adjustment one along 45 the other to suit varying distances between the joists, etc., to which they are to be secured.

4 4 designates the main or body portion of the carrier head of the present invention. Said body portion is of a hollow cylindrical form and is formed with a transverse aperture or passage way 5, which receives the aforesaid hanger member 2, as shown.

6 designates an annular collar disposed at 55 the lower end of the aforesaid main body

portion 4 of the carrier head, and preferably formed integral therewith as shown.

7 designates a screw-threaded shank depending from the main body portion 4, below the annular collar 6, and adapted for the attachment of an electrolier stem. The present construction enables said screw-threaded shank 7, to be made of a much smaller diameter than is required in the main body portion 4, and in consequence the present structure is adapted for the attachment of the standard small size electrolier coupling nipples, instead of necessitating the use of large and special sizes of coupling nipples, as heretofore required in the ordinary type of hangers for outlet boxes, etc.

8 designates a clamping screw engaging a centrally disposed screw-threaded orifice in the upper closed or cap portion 9 of the main body 4 of the carrier head, and adapted to have bearing against the top edge of the hanger member 2, to firmly clamp and bind the carrier head upon the hanger member at a desired point along the same, and in a ready and convenient manner.

10, designates an outlet box, of an ordinary commercial form, provided with the usual central opening in its upper head adapted to encompass the main body 4 of the carrier head, and rest and have abutment upon the annular collar 6, against which it is held by the hanger member 2, under the stress of the clamping screw 8, aforesaid.

In an initial assemblage of parts, the main body 4 of the carrier head is passed through the central opening of the outlet box 10, with the annular collar 6 abutting against the underside of the head of said outlet box. The flat metal strips constituting the hanger member 2 are then passed through the transverse aperture 5 of the carrier head aforesaid.

Having thus fully described our said invention, what we claim as new and desire to secure by Letters Patent, is:

1. The combination of a hanger member adapted for connection to adjacent supports, a carried head having a cylindrical body portion transversely apertured for the reception of said hanger member, a clamping screw fitting a central screw-threaded orifice in the cap portion of said body portion and having bearing upon the top surface of the hanger member, said carrier head having a

5 screw-threaded lower end or shank and an annular collar intermediate of said shank and the aforesaid main body portion, and an outlet box supported on said annular collar.

10 2. The combination of a hanger member adapted for connection to adjacent supports, a carrier head having a cylindrical body portion transversely apertured for the reception of said hanger member, a clamping screw fitting a central screw-threaded orifice in the cap portion of said body portion and having bearing upon the top surface of the hanger member, said carrier head having a reduced and screw-threaded depending shank and an annular collar intermediate of said shank and the aforesaid main body portion, and an outlet box supported on said annular collar.

15 20 3. The combination of a hanger member formed by a pair of flat strips arranged side by side and adjustable one upon the other, a carrier head having a cylindrical body portion transversely apertured for the reception of the flat strips forming the hanger member, a clamping screw fitting a central screw-threaded orifice in the cap portion of

25 said body portion and having bearing upon said body portion and having bearing upon

the top surface of the aforesaid strips, said carrier head having a screw-threaded lower 30 end or shank and an annular collar intermediate of said shank and the aforesaid main body portion, and an outlet box supported on said annular collar.

4. The combination of a hanger member 35 formed by a pair of flat strips arranged side by side and adjustable one upon the other, a carrier head having a cylindrical body portion transversely apertured for the reception of the flat strips forming the hanger 40 member, a clamping screw fitting a central screw-threaded orifice in the cap portion of said body portion and having bearing upon the top surface of the aforesaid strips, said carrier head having a reduced and screw- 45 threaded depending shank and an annular collar intermediate of said shank and the aforesaid main body portion, and an outlet box supported on said annular collar.

Signed at Chicago, Illinois, this 31st day 50 of July, 1914.

FRED L. CAIN.
CONRAD J. DORFF.
